UNITED STATES PATENT OFFICE.

LEONARD CHARLES HARVEY, OF MALDEN, AND HARRY SYDNEY BUCKLEY, OF
WESTMINSTER, LONDON, ENGLAND.

MEANS FOR FEEDING POWDERED FUEL TO FURNACES.

1,389,828.

Specification of Letters Patent.

Patented Sept. 6, 1921.

Application filed August 5, 1920. Serial No. 401,341.

To all whom it may concern:

Be it known that we, LEONARD CHARLES HARVEY, of The Red House, Malden, Surrey, England, and HARRY SYDNEY BUCKLEY, of 5 25 Victoria street, Westminster, London, England, subjects of the King of Great Britain, have invented certain new and useful Improvements in Means for Feeding Powdered Fuel to Furnaces, of which the 10 following is a specification.

Our invention relates to apparatus for feeding powdered coal and like fuel to furnaces and has for its object to insure an efficient regulation and even feed over a wide 15 range from a maximum fuel supply to a minimum supply.

In ordinary powdered coal feeders it is usual to employ a horizontal shaft on which is mounted a screw conveyer so that when 20 the shaft is rotated at a variable speed powdered coal is fed to the delivery pipe in quantities corresponding with the speed of the conveyer. This arrangement, however, necessitates a variable speed motor or other 25 change speed gear.

In certain cases apparatus of this description has been rendered of the constant speed type, variable feed being effected by means of a jaw or shutter at the regulation end of 30 the feed-screw.

The former type, namely, that fitted with variable speed motor, is costly, on account of the special motor and switch gear required, and the latter type, namely, the constant speed feeder, is at times not reliable 35 due to packing of the coal dust at the control jaws or shutters.

The object of the present invention is, therefore, to eliminate the necessity for, and 40 the cost of, a variable speed electric motor and to so arrange for control of fuel feed that there can be no packing at the control valve and that the feed-screw can be operated at a constant speed.

To attain this end, instead of employing a horizontal feed-screw, as is the general practice, we arrange this screw, which is adapted 45 to be rotated in any suitable manner, vertically inside a barrel or tube and we introduce the fuel into this barrel, near the lower 50 end thereof from a hopper having vertical sides and an inclined bottom, and raise the fuel into a box at the upper end. On either

side of this feed and also connected to the box are fixed respectively a fuel delivery 55 pipe, to connect up with the air supply for introduction of the fuel to the burner, and a pipe for the return of the excess of fuel supplied by the central feed screw, the surplus fuel being returned to the lower end of the 60 latter, the said lower end of the feed screw and of the barrel inclosing it being preferably made of slightly larger diameter than the main part thereof. To control the distribution of the fuel, fed to the box by the 65 feed-screw to the delivery pipe and to the by-pass pipe the box is furnished with a swing valve which is so arranged that the supply can be entirely cut off to the delivery pipe or opened up sufficiently to allow the 70 required amount of fuel to pass, or so that the whole quantity of fuel fed by the screw-feeder will be directed into the supply pipe.

To enable the invention to be fully understood we will describe the same by reference to the accompanying drawing, in which:—

Figure 1 is a sectional elevation of fuel feeding apparatus constructed in accordance 80 with the invention.

Fig. 2 is a sectional elevation at right angles to Fig. 1, and

Fig. 3 is a vertical section of the valve-box on the line 3—3, Fig. 2.

a indicates the hopper containing the 85 powdered fuel, the said hopper having vertical sides and an inclined bottom *b*. *c* is the feed-screw which is mounted vertically so that it can rotate in the bearings *d* in the barrel or feed-tube *e*. *f* is a worm driving 90 gear by means of which the lower end of the feed-screw *c* is revolved; *g* is an opening near the lower part of the barrel or tube *e* by means of which the interior of the said tube is placed in connection with the bottom 95 of the hopper *a* so that powdered fuel is fed by gravity from the said hopper into the tube. *n* is the valve box into which the upper end of the feed-tube *e* opens and *i* and *j* are respectively the delivery pipe and the 100 by-pass pipe which open from the valve-box on either side of the feed-tube *e*. The former, that is to say the delivery pipe *i*, conveys the fuel from the box to the burner, while the latter, that is to say the 105 by-pass pipe *j*, is connected at its lower end

to the lower end of the feed-tube *e*, which is by-passed is made of larger diameter than the rest of the tubes, the screw *c* being also made correspondingly larger to fit therein.

k is the valve fitted within the box *h*, the said valve being carried upon the spindle *l* which is mounted in bearings *m* in the box immediately above the center of the feed tube *e* and has keyed upon it, externally of the box, the toothed quadrant *n* with which gears the worm *o* designed to be rotated in the bearings *p* by the hard wheel *q*.

The apparatus operates as follows, that is to say powdered fuel from the hopper *a* passes through the aperture *g* into the feed-tube *e* up which it is then forced, in the direction of the arrow 1 Fig. 2, by the rotating feed-screw *c*. On reaching the upper end of the tube *e* the fuel enters the box *h*, its distribution being controlled by the valve *k*. When the valve is in its central position, shown in Fig. 3, the fuel is directed in more or less equal proportions in the direction of the arrows 2 and 3 respectively into the delivery pipe *i* and the by-pass pipe *j* whence it is delivered as indicated respectively by the arrows 4 to the burner and by the arrow 5 to the lower part of the feed barrel or tube *e*. As will be understood the valve *k* may be swung on its pivot *l* to either side of its central position so as to cut off the supply of fuel to either pipe *i* or *j* partially or wholly as may be desired.

35 Claims:

1. Apparatus for feeding powdered fuel to furnaces comprising a hopper, a vertically disposed feed tube communicating with the hopper, a rotatable feed screw extending through the feed tube, a chamber at the upper end of the feed tube, said chamber being provided with delivery apertures on opposite sides of the feed tube, a delivery tube connected with one of said apertures, a by-pass tube connected with the other of said apertures for returning the fuel to be re-fed by the feed tube, and an adjustable valve in said chamber pivoted substantially in line with the axis of the feed screw, and adapted to close communication between the feed tube and either of said apertures, and means for adjusting said valve to either of

said positions or any desired intermediate position.

2. Apparatus for feeding powdered fuel to furnaces comprising a hopper, a vertically disposed feed tube communicating with the hopper at a point between the ends of said feed tube and having a portion extending below said communication with the hopper, a rotatable feed screw extending through said feed tube, a chamber at the upper end of the feed tube communicating therewith and provided with delivery apertures on opposite sides of the feed tube, a delivery tube connected with one of said apertures, a by-pass tube connected to the other of said apertures and connected with the lower end of the feed tube below its connection with the hopper, and an adjustable valve in said chamber pivoted at a point in line with the axis of the feed screw, and adapted to stand in alignment therewith and to be moved in either direction to close communication between the feed tube and either of said delivery apertures.

3. Apparatus for feeding powdered fuel to furnaces comprising a hopper, a vertically disposed feed tube having an aperture in its side communicating with said hopper and having a portion extending below said communicating aperture, the lower portion of said feed tube being of greater diameter than the upper portion, a feed screw extending longitudinally through said feed tube and having a portion of larger diameter at its lower end, a chamber communicating with the feed tube at its upper end, and provided with delivery apertures in its bottom wall on opposite sides of the feed tube, a delivery tube connected with one of said apertures, a by-pass tube connected at its upper end with the other of said apertures and extending downward parallel with the feed tube and communicating therewith adjacent to the bottom of the feed tube and an adjustable, vertically disposed valve in said chamber pivotally mounted centrally above the feed tube and movable in opposite directions to positions in which one or the other of said delivery apertures is closed.

LEONARD CHARLES HARVEY.
HARRY SYDNEY BUCKLEY.
